J. T. APGAR.
ADJUSTABLE ARCH SUPPORTER.
APPLICATION FILED JAN. 28, 1908.

909,858.

Patented Jan. 19, 1909.

UNITED STATES PATENT OFFICE.

JOHN T. APGAR, OF NEW YORK, N. Y., ASSIGNOR TO GEORGE W. APGAR, OF NEW YORK, N. Y.

ADJUSTABLE ARCH-SUPPORTER.

No. 909,858.

Specification of Letters Patent.

Patented Jan. 19, 1909.

Application filed January 28, 1908. Serial No. 412,960.

To all whom it may concern:

Be it known that I, JOHN T. APGAR, a citizen of the United States, residing at New York city, Manhattan borough, county and 5 State of New York, have invented certain new and useful Improvements in Adjustable Arch-Supporters, of which the following is a clear, full, and exact description.

This invention relates to an adjustable 10 arch-supporter, the object of my invention being to produce an arch-supporter that can be adjusted to fit the various conditions existing in the arch-portion of the human foot. In other words, my improved arch-supporter 15 is adapted for vertical adjustment and also for lateral adjustment.

My improved arch-supporter is constituted to obviate the necessity of riveting the parts together, the elements which constitute my improved arch-supporter being preferably formed by dies.

Other features of improvement will hereinafter appear.

To these and other ends which will herein-after appear, my invention comprises novel features of arrangement and combination of parts which I will proceed to describe and finally claim, reference being had to the accompanying drawing, forming part hereof, 30 wherein—

Figure 1 illustrates a side elevation of my improved arch-supporter; Fig. 2 is a plan view thereof; Fig. 3 is an enlarged cross-sectional detail view, the section being taken 35 on a line *a—a* in Fig. 2; Fig. 4 is an enlarged fragmentary plan view of the pivotal connection existing between the bridge-piece of the supporter, and the adjusting plates; and Fig. 5 is an enlarged fragmentary detail perspective view of the means 40 herein employed to adjust and hold the bridge-piece.

Like numerals of reference indicate corresponding parts in all the views.

Referring to Fig. 1 of the drawing, the 45 numeral 1 indicates the bridge-piece of my improved arch-supporter. The said bridge-piece is adapted to support the under side of the human foot, that is to say, the region between the heel and the ball of the foot as at A, Fig. 1. It is a common fault in the 50 human foot, to have this portion, or bridge, out of shape or fallen, and it is the object of my invention to brace or support the said 55 bridge region when said region has fallen.

This fault is common with heavy people, and is not uncommon with slender people. In order to render the said bridge-piece adjustable I preferably form it out of comparatively thin spring steel not necessarily tempered. The ends of said bridge-piece are turned inwardly, as at 2 and 3, and I shape the said ends into hooks 4 and 5, respectively. To adjust the said bridge-piece vertically, I have herein employed drawing 60 plates 6 and 7, the plate 6 being provided with a catch 8 formed integral therewith, and the plate 7 with a plurality of slots 9 formed in the end 10 adjacent to the catch 8. The end opposite to the catch 8 of the plate 6, terminates in a hook 11 which is adapted to engage the hook 5 on the end 2 of the bridge-piece 1. The remote end of the plate 7 terminates in a hook 12 which is adapted to engage the hook 4 on the end 3 65 of the said bridge-piece 1, the object of the hooked connections at 2, 5, 3 and 4 being to provide a yieldable or pivotal connection in order that the plates 6 and 7 will not buckle when the bridge-piece 1 is pulled, at 70 the ends thereof, toward each other. To pull the ends of the bridge-piece 1 toward each other it is but necessary to force the end 10 upward, whereby the catch 8 will leave its slot 9, and to draw the plates 6 and 7 toward each other and cause another slot 75 to engage the catch 8. The bridge-piece will then be thrown upward, as shown by dotted lines 13 in Fig. 1. The curve of the bridge-piece 1 will be substantially parabolic and 80 the action of drawing the ends of the bridge-piece 1 toward each other, or to allow them to spread, will be to increase, or to decrease, the abscissa of the curve, hence the bridge-piece 1 can be adjusted upwardly or downwardly to meet the requirements existing 85 in a fallen arch.

The arch-supporter as illustrated in Fig. 1 is assumed to be set at about the right height for an ordinary fallen arch. When 100 the weight of the body, in the action of walking, is put upon the bridge-piece 1, the plates 6 and 7 act as tie-rods to resist the end thrust of the bridge-piece.

As the manner of supporting the bridge 105 of the human foot has been described, I will now refer to another feature of my improved arch-supporter. The term arch-supporter implies a device for a double purpose, namely, a device to support the bridge 110

of the human foot and also the arch proper, and for the purpose of supporting the arch an extra upstanding flange is employed. The upstanding flange, which forms part 5 of my invention, comprises a flexible plate 14 having projecting tongues 15, the said tongues being adapted to tightly, but slidably fit into the sockets 16, which are pressed out of the bridge-piece 1, as shown. Projecting from the flexible plate 14 are a plurality of independent longitudinally movable resilient teeth or sections 17, the said teeth 17 being preferably integral with the plate 14 and separated by spaces 18. By 10 making the teeth or sections 17 independent members, and the point of connection 19 thereof with the plate 14, comparatively narrow, the bending of the bridge piece 1 will not be hampered, as it would be if the 15 said upstanding flange was solid, for the reason that the said sections will expand or spread apart fan-like, longitudinally of the bridge-piece, when said bridge-piece is being curved. The arch-supporting flange can 20 be removed from the bridge-piece and another flange substituted if desired. The malformations of the bridge and arch of the foot are not always proportionate; hence it might be necessary to bow the bridge-piece 25 1 but slightly and yet to spread the upstanding flange, composed of the sections 17, considerably. In the arch-supporters now in use the upstanding flange referred to is not adjustable, and therefore great pain to the 30 wearer is sometimes occasioned. If it is desirable to adjust the upstanding flange, of my improved arch-supporter, the said flange can be moved inwardly or outwardly bodily to meet requirements. On the opposite side 35 of the bridge-piece 1, that is, opposite to the arch-supporting flange, I prefer to form a smaller bead 20, which is scarfed, or slotted as at 21, to prevent any resistance to the bending of the bridge-piece 1. The material 40 of which my improved arch-supporter is made is comparatively thin, the thickness herein illustrated being magnified. The mounting of the plate 14 on the bridge-piece 1 in no way interferes with the bending of 45 the said bridge-piece, as it is also preferably of light yieldable steel. The tongues 15 are preferably narrower than the sockets 16.

From the foregoing description it will be seen that my improved arch-supporter is 50 adjustable both vertically and laterally.

The independent yieldable flange sections 55 permit the said flange to accommodate itself to the contour of the arch and yet offer

enough resistance to form a supporting element.

60

It will of course be understood that my improved arch-supporter may, or may not, be covered with a soft material. It will also be noted that my improved supporter as a whole performs the function of giving a 65 springy or cushion action to the wearer, as it is unsupported intermediate the ends thereof.

Having now described my invention, what I claim and desire to secure by Letters Patent is:

1. An arch-supporter, comprising a yieldable vertically adjustable bridge-piece, a hook at each end of said bridge-piece, means adapted to engage said hooks and draw the 75 ends of said bridge-piece toward each other, and an arch-supporting element carried by said bridge-piece.

2. An arch-supporter, comprising a yieldable, vertically, adjustable bridge-piece, a 80 hook at each end of said bridge-piece, adjustable drawing elements adapted to engage said hooks and draw the ends of said bridge-piece together, means adapted to hold said drawing elements in an adjusted position, 85 and an arch supporting element carried by said bridge-piece.

3. An arch supporter adapted for insertion in a shoe comprising a resilient bridge-piece normally adapted to assume various 90 curves, an adjustable drawing element carried by said bridge-piece, said drawing element comprising a non-yieldable element independent of the shoe, and a laterally adjustable slidably mounted arch-supporting 95 element carried by said bridge-piece, said arch-supporting element comprising a resilient member having integral therewith a plurality of resilient tongues.

4. An arch-supporter comprising a bridge-piece adapted to assume various curves, means adapted to curve said bridge-piece, said means being adapted to retain said bridge-piece in a curved position, and a laterally adjustable arch-supporting element 105 100 slidably mounted on said bridge-piece, said arch-supporting element being also mounted for movement longitudinally of said bridge-piece.

Signed at New York city, N. Y. this 25 110 day of January 1908.

JOHN T. APGAR.
